(57) **CLAIM**

We claim the ornamental design for a computer docking station, as shown and described.

DESCRIPTION

FIG. 1 is a perspective view of a computer docking station embodying the present invention.

FIG. 2 is a top view of the computer docking station shown in FIG. 1.

FIG. 3 is a bottom view of the computer docking station shown in FIG. 1.

FIG. 4 is a front view of the computer docking station shown in FIG. 1.

FIG. 5 is a rear view of the computer docking station shown in FIG. 1.

FIG. 6 is a left side view of the computer docking station shown in FIG. 1; and,

FIG. 7 is a right side view of the computer docking station shown in FIG. 1.

Portions of the computer docking station illustrated in broken lines form no part of the claimed design.
